DESIGN FOR A GAME BOARD

Howard J. Peo, Rochester, N. Y.

Application April 7, 1941, Serial No. 100,180

Term of patent 7 years

To all whom it may concern:

Be it known that I, Howard J. Peo, a citizen of the United States, residing at Rochester, in the county of Monroe and State of New York, have invented a new, original, and ornamental Design for a Game Board, of which the following is a specification, reference being had to the accompanying drawing, forming a part thereof.

The dominant feature of this design resides in the part shown in full lines.

I claim:

The ornamental design for a game board, as shown and described.

HOWARD J. PEO.
